UNITED STATES PATENT OFFICE.

FREDERICK A. GERCICH, OF OAKLAND, CALIFORNIA, ASSIGNOR TO HAMMER-BRAY COMPANY, OF OAKLAND, CALIFORNIA, A CORPORATION OF CALIFORNIA.

GAS-KINDLING-BURNER INSTALLATION.

Application filed July 26, 1926. Serial No. 125,071.

My invention relates to a gas kindling burner and particularly to the mounting of the same in a gas stove having a fire box for solid fuel associated therewith.

5 An object of the invention is to provide, in a stove of the class described, a gas kindling burner so mounted that the connections therefor will be inconspicuous and will in no way interfere with the normal use of the stove.

10 Another object of the invention is to so position the control cock for the kindler burner that it will be most accessible and at the same time will not detract from the appearance of the stove.

15 The invention possesses other objects and features of advantage, some of which, with the foregoing, will be set forth in the following description of the preferred form of my invention which is illustrated in the drawings accompanying and forming part of the specification. It is to be understood, however, that I do not limit myself to the showing made by the said drawings and description, as I may adopt variations of the preferred form within the scope of my invention as set forth in the claims.

Referring to said drawings,

20 Figure 1 is a fragmentary front view of a stove having a kindler installed thereon in accordance with my invention.

Figure 2 is a sectional view taken on the line 2—2 in Figure 1.

25 Figure 3 is a fragmentary plan view, partly in section, of the installation.

Figure 4 is a plan view of the gas manifold at the front of the stove.

30 Figure 5 is a fragmentary vertical sectional view through the stove showing a slightly modified form of kindler pipe connection.

35 As herewith particularly disclosed, the device of my invention is incorporated in a combination stove 4 having a cooking top 6 beneath a portion of which is provided a top gas burner chamber 7 and beneath another portion of which is provided a fire box 8 arranged for the combustion of solid fuel. The chamber 7, it will now be noted, is preferably comparatively shallow, the plane of the bottom wall 11 thereof intersecting the fire box intermediate its fuel holding portion. The wall 11, besides defining the bottom of the chamber, is also utilized for the 40 support of a drip pan 10 and defines the top

of a warming closet or oven 22 which is positioned directly under the chamber 7, such oven being here shown provided with a drawer 23. Mounted on the stove in front of the chamber 7 is the usual horizontally disposed burner supply manifold 12 having gas cocks 13 arranged for the delivery of fuel to the different burners of the chamber, it being noted that corresponding parts of the cocks are in alignment in accordance with usual practice.

45 To facilitate the ignition and combustion of material in the fire box, a kindler 9 is provided, such kindler being arranged to project gaseous fuel into a part of the fire box 50 normally occupied by solid fuel, so that the latter fuel may be ignited when the former is burning therein. The kindler 9, it will now be noted, comprises a manifold or pipe portion 14 having fuel discharge nozzles or jets 16 extending generally horizontally therefrom. The kindler pipe 14 is preferably, and as here shown, positioned at the outer side of the side 17 of the fire box below the wall 11, such side being common to the 55 fire box and chamber 7 above the wall 11. The side wall 17, it will be noted, is perforated opposite the pipe 13 to receive the jets 16, while a guard plate 18 is provided within the fire box, such plate being perforated in the path of discharge of the jets. It will now be seen that with the kindler thus formed and positioned, discharge of the fuel gas may take place in the lower portion of the solid fuel in the fire box and yet the 60 kindler pipe is inconspicuous and is not subject to excessive heat as would be the case if it were either in the fire box or in the burner chamber 7.

65 The kindler is preferably supplied with gas from the supply manifold 12 and is connected thereto by means of a pipe 19 and a cock 21. As here shown, the cock 21 is similar to the cocks 13 and is connected to the manifold at a point thereon in alignment 70 with the latter cocks. In this manner, the kindler control cock 21 is presented for most convenient manipulation and is not made conspicuous by reason of an isolated positioning thereof, as has heretofore been the 75 usual practice with such cocks.

80 The oven 22, it will be noted, extends both above and below the kindler 9, so that the drawer 23 must be spaced from the side wall 17 to permit its movement in the oven. To 85

close the gap thus provided at the front of the stove between the drawer and side wall 17, a casing 24 is preferably provided, such casing extending from at least the plate 11 to the bottom of the oven and between the drawer and fire box. The kindler pipe portion 26 opposite the jets and adjacent the drawer is conveniently utilized to provide a guiding means for the adjacent drawer side to thereby assist in directing the in and out movement of the drawer.

The supply manifold 12, it will now be noted, is preferably capped at the end remote from the fire box and is directed downwardly from a point thereon adjacent the point of attachment of the cock 21 thereto to connect with a horizontally disposed supply pipe 27 which extends from the back of the stove through the space between the wall 17 and the drawer and below the kindler pipe and through the casing member 24, it now being noted that the kindler connecting pipe 19 also extends through said wall and then turns upwardly to lie behind, and thus be at least partly concealed by, the vertical portion of the supply manifold. In this manner, undue pre-heating of the gas in the manifold is avoided, and a maximum concealment of the various pipes is effected.

In Figure 5, I have shown a modified form of connection for the kindler pipe. In this embodiment the pipe 19' which connects the kindler pipe 14' with the manifold passes through an extended portion 30 of the casing 24' disposed in front of the burner chamber 7, and extends downward through the plate 11 to the pipe 14'. With this form of connection the pipe 19' is practically entirely concealed.

I claim:

1. In a stove provided with a cooking top, a fire box and a top gas burner chamber underlying said top, gas burners in said chamber, a kindler burner arranged to deliver gaseous fuel within said fire box, a gas supply manifold at the front of said stove, and supply cocks for all said burners operatively disposed between said manifold and burners and having corresponding parts thereof in rectilinear alignment.

2. In a stove provided with a cooking top, a fire box and a top gas burner chamber underlying said top, gas burners in said chamber, a kindler burner operatively associated with said fire box, a common gas supply manifold for said burners, and aligned supply cocks operatively disposed between said manifold and all said burners.

3. In a stove, a cooking top, a fire box and a gas burner chamber defined below said top and having a common wall, burners in said chamber, a gas burner having the manifold portion thereof positioned below said chamber and adjacent said wall, noz-

zles extending from said burner manifold into said box and arranged to discharge thereinto, a common gas supply manifold for said burners, and supply cocks operatively disposed between said manifold and all burners and having corresponding portions thereof in alignment in front of said burner chamber.

4. In a stove, a cooking top, a fire box and a gas burner chamber defined below said top and having a side wall portion of said fire box common between them, an oven below said chamber having a different side wall portion of said fire box in common between it and said fire box, a gas kindler burner having the manifold portion thereof positioned in said oven adjacent said wall, nozzles extending from said burner manifold into said box and arranged to discharge thereinto, a supply manifold for said burners, means connecting said manifold and burners, and aligned supply cocks for all said burners operatively disposed in said connecting means and above the level of said oven.

5. In a stove, a cooking top, a fire box and a top gas burner chamber defined below said top in contiguous relation, burners in said chamber, an oven defined below said chamber in contiguous relation thereto and to said fire box, a drawer slidably carried in said oven in spaced relation from said fire box, a gas kindler burner arranged to deliver gaseous fuel within said fire box and having the manifold portion thereof disposed in said oven between said drawer and fire box, a casing disposed at the front of the stove between said drawer and fire box, a burner supply manifold disposed in front of said chamber, and horizontally aligned cocks operatively disposed between said manifold and all said burners and entirely in front of said chamber.

6. In a stove, a cooking top, a fire box and a top gas burner chamber defined below said cooking top in contiguous relation, an oven defined below said chamber in contiguous relation thereto and to said fire box, a drawer slidably carried in said oven in spaced relation from said fire box, a gas kindler burner arranged to deliver gaseous fuel within said fire box and having the manifold portion thereof disposed in said oven between said drawer and firebox, said manifold portion providing a guide for said drawer at the adjacent side thereof.

7. In a stove, a cooking top, a fire box and a top gas burner chamber defined below said top in contiguous relation, an oven space defined below said chamber in contiguous relation thereto and to said fire box, a drawer slidably carried in said oven space in spaced relation from said fire box, a casing disposed at the front of said stove between said drawer and fire box, a kindler burner

disposed between said drawer and fire box and arranged to deliver gaseous fuel to the fire box, a fuel supply manifold extended in front of said chamber, connecting means 5 extending from said burner through said casing and upwardly in front thereof to a connection with said manifold, a fuel supply pipe extending forwardly through said stove between said drawer and fire box and

through said casing, and connecting means 10 extending upwardly from the forwardly extending end of said pipe to said supply manifold and disposed in front of said first connecting means.

In testimony whereof, I have hereunto set 15 my hand at Oakland, California, this 14th day of July, 1926.

FREDERICK A. GERCICH.
